METHOD AND MEANS FOR MAKING
BRASSIÈRESWilliam Rosenthal, New York, N. Y., assignor to
Maiden Form Brassiere Co., Inc., New York,
N. Y., a corporation of New York

Application March 17, 1933, Serial No. 661,421

3 Claims. (Cl. 223—19)

This invention relates to a brassière of knitted fabric in which the pockets for the bust are free of seams. It also relates to an improved method of making such a brassière by means of which the pockets may be shaped as desired, irrespective of their original shape as knit, and to a method of shaping the pockets to give them the desired form and characteristics not found in the original knitted fabric.

10. The fabric from which the brassière of this invention may be made can be knitted on a circular knitting machine of the type which produces what is known as "gussets". That is to say, pockets which are knit into the fabric during the knitting operation without any seams, such as would be required in order to form pockets in flat knitted fabric.

Accordingly, one of the objects of this invention is the creation of a novel brassière having 20. seamless pockets.

Another object of this invention is the creation of a novel brassière having seamless pockets made of a knitted fabric formed to give the desired breast receiving and supporting configuration.

Another further object of this invention is the creation of a method and the provision of means for making and properly forming a brassière having seamless pockets.

These and many other objects are secured by the invention hereinafter disclosed.

This invention resides substantially in the combination, construction, arrangement and relative location of parts, as well as in steps, sequence of steps and combination of steps all as will appear more fully hereinafter.

Referring to the drawings in which the same reference numerals will be used throughout the several views to indicate the same or similar parts,

Figure 1 is a diagrammatic illustration of a piece of fabric knit on a circular knitting machine showing the pockets in their original, irregular conical shape;

Figure 2 is a view of my novel stretching frame over which the fabric is stretched during the process whereby it is given its final shape and characteristics;

Figure 3 illustrates diagrammatically two pockets cut from the original knitted material and stretched upon the form of Figure 2;

Figure 4 is a sectional view taken along the line 4—4, of Figure 2;

Figure 5 illustrates a variant possible embodiment of the construction shown in Figure 4;

Figure 6 illustrates diagrammatically one manner in which the stretched fabric may be cut to separate the portions which are used to form the respective pockets of the brassière;

Figure 7 shows one form of a completed brassière and the manner in which the pocket pieces are combined with the rest of the brassière construction;

Figure 8 shows another form of completed brassière and the manner in which the pockets may be combined with the rest of the brassière construction;

Figure 9 is a view of a second possible form of a stretching frame over which the fabric may be stretched during the process whereby it is given its final shape and characteristics; and

Figure 10 is a view of a third possible form of stretching frame for also accomplishing the desired stretching with a part thereof broken away.

As pointed out in my copending application for United States Letters Patent Serial No. 650,966, filed January 10, 1933, knitted fabric produced by circular knitting up to the time of my invention had never been practical for brassières for the reason that the knit seamless pockets could not be given the proper shape and the elasticity and other characteristics of the fabric in its original knitted form, allowed the pockets to stretch and to lose whatever shape they had.

By the invention of my application above mentioned I pointed out how I overcame these defects and procured a brassière of knitted fabric with seamless pockets of the size and shape desired, irrespective of their original knitted shape and which would retain their shape thereafter. Such pockets being seamless all possibility of irritation of the wearer's skin was accordingly obviated.

As a result of further experimentation and investigation, I have discovered certain further improvements in the method of and means for making knit brassières having seamless pockets as well as in the resulting brassières which I now disclose.

Turning to Figure 1 it will be noted that a piece of knit unprocessed material is shown which has two pockets 1 and 2 which consists of excess seamless material formed during the knitting. This fabric produced, as described above, with the integral seamless pockets of irregular conical form is first dyed and then cut to separate from the body of the material the desired part including the two similar pockets. Then the cut edges are sewn to prevent ravelling and the

fabric is stretched over the frame 3 as shown in Figure 3, which frame may be made of any suitable material, and which has the outline desired for the pockets of the finished brassière found in its upper edge 4. For this purpose I have found it desirable to construct and form my frames as shown in either Figures 2, 9 or 10. Each of these frames I provide with serrated strips 5 running longitudinally of and parallel to the base thereof. The serrations on these strips are outwardly projecting and are adapted to engage with the fabric that is stretched on the frame and to hold said fabric in stretched condition.

In Figure 2, these serrated strips 5 are secured to an adjustable cross rod 6 which is secured to the vertical sides 7 of the frame 3 at different heights by means of screws 13. Each of the vertical sides 7 is provided with a plurality of threaded holes 8 disposed over one another into a given set of which the screws 13 may be screwed. To insure firm contact between the flat surfaces of sides 7 and the flat surface of rod 6 the flat ends of cross rod 6 are slightly joggled as shown at 6' to provide feet 11. The frame 3 is also provided as shown at its midlength with an integral vertical cross member 9 which also has adjacent the end thereof which joins the base of frame 3 a plurality of threaded holes 10 disposed over one another. So that cross rod 6 may be maintained in alignment with the base of frame 3 it is besides the joggling at each end thereof also joggled at its midlength as shown at 12, and may at this point be secured by another one of the screws 13 to the appropriate hole 10 in member 9. The cross rod 6 is of course, provided with the necessary holes at each foot 11 and in the center to permit of the passage of the necessary screws 13 therethrough and into the appropriate holes 8 in sides 7 and hole 10 in member 9. Thus by securing screws 13 into a selected set of holes 8, 10, the height of cross rod 6 may within the limits of the holes be adjusted as desired in a vertical direction.

In a like fashion frame 3 is provided at upper edge 4, adjacent to and on each side of cross member 9, with a plurality of holes 14, horizontally disposed one next to the other. Cross member 9 is also provided near its lower end and just above the uppermost hole 10 therein with the longitudinally extending horizontal arms 15, each of which also is provided with a plurality of holes 15' horizontally disposed one next to the other. Secured by screws 18 to frame 3 and to each of arms 15, are vertical rods 16, which run parallel to member 9, are adjustable horizontally and also carry serrated strips 17. As is apparent these vertical rods 16, by selectively screwing screws 18 into selected holes 14, 15' may be horizontally adjusted so that said rods within the limits of the holes may be disposed in any predetermined relation with respect to each other and/or with respect to cross member 9.

Carried by the uppermost end of each of rods 16 are the pin like hooks 19 which are adapted to engage and hold the material in stretched condition. Similarly the frame 3 at the ends of upper edge 4 is provided with the hooks 20 for receiving and holding the material when stretched on the frame. By providing the serrated strips 5 and 17, on the respective rods 6 and 16, which rods are adjustable as just pointed out, I am able to adjustably arrange for a predetermined amount of stretching at one time of either both pockets or a single pocket.

To insure a firm holding of the material I also

provide adjacent to and secured by screw 21' at the hole immediately above that to which cross rod 6 is secured on cross member 9, the element 21 which is provided with prongs 22, 23, 24 and 25. This member will aid in receiving and holding opposed portions of the pocket material in stretched condition under tension at the midlength point along and just above the base of frame 3. In place of this construction, which may be observed in Figs. 2 and 4, I may substitute and use with equal effect the variant embodiment shown in Fig. 5, wherein, instead of using a single element 21 disposed on one side of cross member 9 I employ two elements 46 and 47 disposed on opposed side of member 9 and secured thereto by screw 48 and nut 49. These elements are also provided with holding prongs 22', 23' and 24', 25' respectively so that the same desired effect may be procured thereby without the necessity of having the prongs of different lengths depending on whether they are to be bent backward or forward.

The circular knit fabric comprising either two unformed pockets, as shown in Fig. 1, or a single unformed pocket as the case may be, is stretched over the frame 3, as shown in Fig. 3, and the material thereof caught on the serrations, prongs, etc. Screws 13 are unscrewed and cross rod 6 is pulled down until the fabric is firmly stretched over the frame 3 to the desired degree with the pockets or pocket taking the outline of the upper edge 4 thereof. Cross rod 6 is then secured with the fabric in this stretched condition by screwing screws 13 into the appropriate set of holes 8, 10.

In doing this, of course, the fabric is caught on the pins 19, 20, 22, 23, 24 and 25 or 19, 20, 22', 23', 24' and 25', as the case may be, as well as by the appropriate serrated strips 5 and 17. In the event that two unformed pockets are being stretched all of these holding devices are brought into play. In the event, however, that but one pocket is being stretched, then but one-half of the frame either right or left need be used. It will, of course, be understood that after the rods 6 and 16 have once been adjusted as desired the frame may be repeatedly used without further adjustment for other pieces of fabric to be successively treated. When the fabric is stretched, as above pointed out, the desired outline is given to the pockets and they are flattened as required so that the material may thereafter, when subsequently removed from the frame, be conveniently cut and otherwise practically commercially treated and handled.

The fabric thus stretched is steamed or otherwise heat treated and then permitted to cool and dry upon the frame.

It will also be understood that due to the fact that the material after blocking is flattened that a number of pockets after removal from the frame can be stacked and simultaneously and uniformly cut as desired, thus reducing manufacturing time and expense.

When it is removed it will be found the pockets have lost their original shape and outline and have permanently taken the outline of edge 4 of the frame and also, instead of being generally conical in shape, are exceedingly flat, as shown in Fig. 3. It will be found that the pockets will retain this outline and flatness throughout the life of the brassière and will not revert to the original shape.

After the fabric has been steamed, set, and removed from the frame the individual pockets

are cut therefrom, as shown in Fig. 6, by cutting either along the lines of cut 26, 27, for both sides, or 28, 29 and 29' for one side and 30 and 31 for the other side, to produce pockets either of the type 5 32 or 33 (see Figs. 7 and 8) as the case may be. Thus, by changing the manner of cutting the material after treatment on the frame, the final 10 outline of the pocket may be selectively arranged for. When cut the pockets, if not already secured together, may be sewn together and connected to the rest of the brassière to form the completed articles as shown in Fig. 7 or Fig. 8.

In many instances it will be found desirable 15 to use a stretching form of solid material rather than a skeleton framework. In Fig. 9 I have shown a solid form provided with a multiplicity of holes 34, which will permit of steam treatment of the material stretched on that form. Steam or hot air used for drying purposes may readily 20 pass transversely through said solid form by means of the holes 34 which permit of the appropriate treatment of the material stretched thereover. The necessary serrated strips, as well as the pins, are provided so that this embodiment 25 may be used in substantially the same fashion as that of Fig. 2.

In Fig. 10, a still further embodiment is shown 30 wherein the form, instead of being made solid, comprises two partially curved sheets 35 which are joined along the upper edges 4 and which sheets also are perforated with holes 34 to permit 35 of the heat treatment of the material stretched on the frame. With this embodiment a chamber is formed between the plates 35 in which a heating or drying unit or any other available desired apparatus may be contained for treating the material as stretched upon the complete framework.

When embodiments such as those shown in 40 Figs. 9 and 10 are used the material of course, will permanently lie substantially against the flat sides of the frame, and if desired, could be pressed thereagainst or otherwise subjected to such treatment as can be advantageously practiced when the material is stretched over a flat body. Also when using these embodiments either 45 holes must be provided through the solid body or sheets for the prongs of elements 21 to extend through or else the two element construction of holding devices 46, 47 of Fig. 5 must be employed. It will be noted that apart from the differences 50 mentioned the embodiments of Figs. 9 and 10 are otherwise the same as that of Fig. 2.

Employing any one of the frame or form 55 embodiments above described I am able to convert a fabric which is utterly useless for brassières into a very useful type of fabric for that purpose and obtain a brassière having seamless pockets of any desired outline by appropriate treatment 60 and cutting, irrespective of their shape and outline in the fabric as originally cut.

Since the original size and shape of the pockets have little effect within wide limits, upon the 65 size and shape of the finished pockets, I am able to produce a large variety of pocket sizes and shapes from the identical fabric, thus greatly simplifying and reducing the cost of manufacture.

The pockets thus shown, shaped and appropriately cut, may, as above stated, be incorporated 70 in any desired brassière construction, such as that shown in Figs. 7 or 8. In Fig. 7 the brassière consists of two pockets 32 attached to each other as shown at 36. The free ends of the pockets are 75 attached to additional fabric back bands 37 and

38. One of these back bands to wit, 38, terminates in a piece of elastic 39, the free end of which is secured to the free end of back band 37 by cooperating hooks and eyes as at 40.

The usual shoulder straps 41 may of course, 5 also be provided. As shown these shoulder straps if desired may also be provided with elastic elements 42 interposed in the length thereof near the end thereof so as to lend to said shoulder straps a certain degree of adjustability. In Fig. 10 10 8 the pockets 33 are obtained by cutting the fabric on one side of the frame along the lines 28, 29 and 29' and that on the other side of the frame along the lines 30 and 31. The pocket formed, if not already secured together may be 15 secured along the line 42. Secured to these pockets along the bottom edges thereof is a strip 43 which extends past the pocket around the wearer's body and replaces the usual back bands. Secured to each free end of the strips are elastic 20 elements 44 which are adapted to be joined together at the free ends thereof by tabs 45 carrying the necessary hook and eye. The embodiment also is provided with shoulder straps 41 and the elastic elements 42' so as to give a certain 25 degree of adjustability to the shoulder straps. In the embodiment shown in Fig. 8, the elimination of the usual back bands presents a brassière of lighter, more dainty and fragile construction. The proportions of the respective brassière will, 30 of course, be determined by the dimensions of the different elements, as well as by the shapes and sizes to be produced whereas, the size, shape and outline of the pockets themselves are determined by the outline and dimensions of the particular stretching frame described above.

It will be understood, of course, that the process herein described contemplates the production of the desired pockets, either individually or in pairs, as well as in numerous other ways within 35 the scope of the invention.

It will also be understood that variations in the construction of the different stretching frames may be made in a number of possible directions so that the same general desired results may be attained and that the different frames herein disclosed may with equal success possibly be used for purposes other than those herein described. Moreover, I am of course, aware that many changes in the details of constructions and relative arrangements of parts, as well as in the steps, 45 sequence or combination of steps may readily suggest themselves to those skilled in the art, and I do not, therefore, desire to be limited to the exact details disclosed by way of illustration but rather to the scope and spirit of the invention as I define it in the appended claims.

What I seek to secure by United States Letters Patent is:

1. The method of producing a sized and shaped 60 seamless brassière pocket from knitted fabric having pockets therein of a shape other than that of the finished pocket, which consists of stretching said pocket to size and shape upon a frame, then steaming and then drying said pocket while stretched upon the frame, and thereafter cutting the material thereof along appropriate lines of cut to provide a pocket of the desired configuration.

2. The method of producing a sized and shaped 70 brassière having seamless pockets from knitted fabric not suited to such use in its natural state, said fabric having in its natural state pockets therein of a shape other than that of the finished pocket, which consists of stretching the fabric and its pockets to size and shape upon 75

a frame while wet, drying the fabric while it is stretched and sized, and thereafter cutting the fabric along appropriate lines of cut, and uniting the cut parts to produce a brassière of the desired configuration.

3. In an article of the type described, a base rod, a plurality of integral vertical rods secured to said base rod, integral V-shaped rods extending

between each pair of vertical rods at their upper ends, and adjustable means carried by said V-shaped rods and said vertical rods for engaging with and tensioning a fabric, said V-shaped rods being provided with prongs at each end thereof for engaging with the fabric to be stretched over the frame.

WILLIAM ROSENTHAL.
